UNITED STATES PATENT OFFICE.

JOHN O. LINDEN, OF PROPHETSTOWN, ILLINOIS.

SNOW LOADER AND UNLOADER.

No. 825,926.

Specification of Letters Patent.

Patented July 3, 1906.

Application filed August 2, 1905. Serial No. 272,321.

To all whom it may concern:

Be it known that I, JOHN O. LINDEN, a citizen of the United States, and a resident of Prophetstown, in the county of Whitside and State of Illinois, have invented a new and Improved Snow Loader and Unloader, of which the following is a full, clear, and exact description.

This invention relates to improvements in machines for cleaning snow from streets or roads and loading the snow into a wagon, from which it may be unloaded at any suitable place, the object being to provide a machine of this character so constructed that the loading and unloading will be practically automatic and in which the working parts may be controlled from the driver's seat.

Other objects of the invention will appear in the general description.

I will describe a snow loader and unloader embodying my invention and then point out the novel features in the appended claims.

Reference is to be had to the accompanying drawings, forming a part of this specification, in which similar characters of reference indicate corresponding parts in all the figures.

Figure 1 is a side elevation of a snowloader and unloader embodying my invention. Fig. 2 is a longitudinal section thereof on the line 2 2 of Fig. 3. Fig. 3 is a plan. Fig. 4 is a detail showing a chain-gearing employed, the same being a section on the line 4 4 of Fig. 3. Fig. 5 is an end view of one of the snow-carrier plates, and Fig. 6 is a rear view thereof.

Referring to the drawings, 5 designates the wagon box or body, mounted on the front wheels 6 and rear wheels 7. The box or body has a solid bottom 8; but the rear end-board is provided with a discharge-opening 9, and there is an opening 10 at the front of the bottom, through which the carrier now to be described may pass. This carrier consists of endless chains 11, movable along the upper side of the bottom 8, and connected to the chains at suitable distances apart are upwardly-extended carrier-bars 12. At the forward portion the chains pass over sprocket-wheels 13, and at the rear end they engage with driving sprocket-wheels 14, mounted on a shaft 15, arranged rearward of the body. On one end of the shaft 15 is a worm-wheel 16, designed to be engaged by a worm 17 for driving the carrier forward in the wagon-body while loading the snow or carrying it toward the forward end of the body. The worm 17 is mounted on a shaft consisting of

two pivotally-connected sections 18 19, the section 18 being movable upward to disengage the worm 17 from its wheel, as will be hereinafter described. Loosely mounted on the shaft-section 19 are bevel-pinions 20 21, the pinion 20 engaging with a large gear-wheel 22 and the other pinion 21 engaging with a smaller gear-wheel 23, these gear-wheels being connected to one of the rear wheels of the wagon. The object of this arrangement is to change the speed of movement of the carrier—that is, in some cases a slow motion is required, while in other cases the carrier may be moved at a greater speed.

To place either one of the pinions in driving connection with the worm-shaft, I employ a clutch mechanism—that is, the pinion 20 is provided with a clutch-section 24, designed to be engaged by a clutch-section 25 on a ring 26, mounted to slide on the shaft-section 19, but adapted to rotate therewith. On the forward side of the ring 26 is a clutch-section 27, that may be placed in engagement with the clutch-section 28 on the pinion 21. From the ring 26 a shifting rod 29 extends forward and connects with the lower end of a shifting lever 30, pivoted on the vehicle-body adjacent to the driver's seat. On the shaft 15 is a pinion 31, meshing with a pinion 32 on a stud extended outward from the vehicle-body, and on this stud is a sprocket-pinion 33, from which a chain 34 extends to a sprocket-pinion 35, loosely mounted on a sleeve 36, which forms the hub of one of the rear wheels. On this sprocket 35 is a clutch member 37, designed to be engaged by a clutch member 38, slideable on the rear axle, but rotating therewith. The clutch member 38 is provided with an annular channel into which pins from one member of an angle-lever 39 engage. This angle-lever 39 is pivoted on a lug 40, and from the outwardly-extended portion of the angle-lever a draw-rod 41 extends forward and connects with a lever 42, mounted in the vehicle-body near the driver's seat. This chain-gear above described is designed to move the carrier in the vehicle-body rearward to unload the snow through the opening 9, and therefore when the clutch member 38 is thrown into engagement with the clutch member 37 the worm 17 must be at the same time thrown out of gear with its wheel. For this purpose the worm-shaft 18 is mounted in a bearing 43, mounted to slide on a bracket 44, attached to the vehicle-body.

As clearly indicated in Fig. 4, a bolt passes

from the bearing 43 and through a slot in said bracket 44. Pivots connected to the bearing is a horizontally-disposed member having an angle-lever 45, and the vertically-disposed member of said lever has a rod connection 46 with the lever 42.

When the snow is discharged into a vehicle-body by the loader, to be hereinafter described, it is preferable to somewhat compress it into cakes or sheets. Therefore I employ a presser consisting of upwardly-divergent endless aprons 47 48, each provided with a series of cross-slats 49. The aprons are mounted on endless chains, the chains of the rear apron 47 engaging at the upper portion of sprocket-pinions 50 and at the lower portion with sprocket-pinions 51. The upper portion of the chains for the apron 49 engage with sprocket-pinions 52 and at the lower portion with sprocket-pinions on a shaft 53, which is mounted on bearings movable toward and from the rear apron and held yieldingly by means of springs 54. The shafts for the upper sprocket-pinions are mounted in frames 55, extended upward from the vehicle-body, and on the shaft 53 is a pinion 56, meshing with a pinion 57 on the shaft for the lower sprocket-pinions of the rear apron, and on this shaft is a sprocket-pinion 58, in which a chain 59 extends to a driving-sprocket 60, rigidly attached to the rear axle.

I will now describe the means for loading the snow into the vehicle body or box. The loader comprises a frame 61, which is inclined upward and forward and is mounted on supporting-wheels 62, from the axle of which arms 63 project forward and have downwardly-turned ends for detachably engaging in socket members 64, secured to the rear end of the vehicle-body. Brace-bars 65 are connected at their upper ends to the side members of the frame 61 and at their lower ends to the arms 63. Attached to the lower end of the frame 61 is a curved scraper-plate 66, designed to scrape the snow from the street or road and discharge the same onto an endless carrier movable on the frame 61. This carrier consists of a plurality of slats 67, arranged close together, so as to form a practically-tight piece for the snow to rest upon, these slats being pivotally connected together to form a sprocket-chain which at the upper end passes over pinions mounted in the upper end of the frame 61 and certain links for notches 68 for receiving the teeth on sprocket-wheels 69, mounted on a shaft 70, arranged at the lower portion of the frame 61, and on this shaft 70 is a pinion 71, from which a chain 72 passes to the driving-wheel 73, attached to the rear axle. On certain of the slats 67 at the ends are upwardly-extended blocks 74, to which upwardly-extended carrier-plates 75 are yieldingly attached. These plates are mounted to rock on shafts 76, mounted in the blocks 74, and they are

yieldingly held by means of plate-springs 77, extended upward from the shafts 76 and engaging against the rear sides of the plates.

In the operation as the machine moves forward the snow will be scraped up by the scraper 66 and discharged onto the endless carrier, from which the snow will pass to the compressor. At this time, if desired, the carrier in the vehicle-body may remain stationary, as the clutch-carrying ring 26 may be in an intermediate position, as indicated in Fig. 4. When a sufficient amount of snow is discharged into the rear portion of the body, the clutch-ring may be moved to place either one of the pinions 20 or 21 into driving connection with the worm-shaft, so that the carrier in the body may move forward, carrying the snow toward the forward end of the body. In unloading the loader may be detached from the vehicle, and then as the vehicle moves forward and the pinion 35 is placed in driving connection with the sleeve 36 through the medium of the clutch-section and the worm 17 detached from its wheel, as before described, the endless carrier in the body will be moved rearward to discharge the snow through the opening 9. It may be here stated that the snow-loader may be employed for connection with a number of wagons—that is, when one wagon is on its way to a place of discharge the loader may be connected to another wagon for scraping up the snow.

Having thus described my invention, I claim as new and desire to secure by Letters Patent—

1. In a machine of the character described, a wheel-mounted body, an endless carrier movable along the bottom thereof, means for moving the carrier in a forward direction, and means for moving the carrier in a reverse direction.

2. In a machine of the character described, a wheel-mounted body, an endless carrier movable over the bottom thereof, means for moving the carrier forward, means for changing the speed of movement in a forward direction, and means for moving the carrier in reverse direction.

3. In a machine of the character described, a wheel-mounted body, an endless carrier movable over the bottom thereof, means for causing the movements of the carrier, and snow-pressing devices arranged at the rear end of the body.

4. In a machine of the character described, a wheel-mounted body, an endless carrier movable over the bottom thereof, means for causing back-and-forth movements of the carrier, a snow-compressor comprising two upwardly-extended divergent endless aprons, and means for causing the movements of the aprons.

5. In a machine of the character described, a wheel-mounted body, an endless carrier movable along the bottom of the body,

sprocket-wheels on which the carrier is mounted, a worm-wheel on a sprocket-wheel shaft, a worm for engaging therewith, a worm-shaft having an upwardly-swinging portion, bevel-pinions mounted loosely on said shaft, a large gear-wheel mounted on a rear wheel of the machine for engaging with one of said pinions, a small gear-wheel on said rear wheel of the machine for engaging with the other of said pinions, a clutch movable on the shaft for engaging with either one of said pinions, a clutch-controlled reversing mechanism, and means for simultaneously releasing the worm from its wheel and throwing the reversing-gear in operative connection.

6. In a machine of the character described, a wheel-mounted body, a loader comprising a wheel-mounted frame detachably connected to said body, an endless carrier movable over the frame, yielding carrier-blades on the carrier, means for causing movement of the carrier, and a scraper at the lower end of the frame.

7. In a machine of the character described,

a wheel-mounted body, a loader comprising an inclined frame, an endless carrier movable around said frame, spring yielding blades or plates on said carrier, means operated by the wheels on said loader for operating the carrier, and a curved scraper on the lower end of the frame.

8. In a machine of the character described, a wheel-mounted body, an endless carrier movable over the bottom of said body, snow-pressers arranged at the rear portion of the body, a loader comprising an inclined frame extended over said compressor, an endless carrier on said frame, wheels on which the frame is mounted, a driving connection between said wheels and the carrier, and a scraper on the lower end of the frame.

In testimony whereof I have signed my name to this specification in the presence of two subscribing witnesses.

JOHN O. LINDEN.
